MITER BOX

Frank J. Gammache, deceased, late of Manheim Township, Lancaster County, Pa., by Magdalena Gammache, executrix, Lancaster, Pa., assignee or to Magdalena Gammache, Country Club Heights, Lancaster, Pa.

Application November 12, 1940, Serial No. 365,362

2 Claims. (Cl. 143—86)

This invention relates to miter boxes, and particularly to miter boxes constructed primarily from sheet metal or other similar material.

The broad primary object of the invention is the production of such a sheet metal miter box which is adapted for economical manufacture primarily by sheet metal stamping operations, is of extremely rugged sturdy construction, and which will retain its shape without becoming bent or sprung, and accordingly will remain accurate, throughout a long period of use.

More specific objects are: to provide in such a sheet material miter box a novel arrangement of corrugations which, in addition to reinforcing and stiffening the entire miter box frame or body, also serve as guide channels or means cooperating with the movable clamp members, and serve to rigidly brace and maintain the stationary clamp members or means in fixed upright position against pressure exerted by their respective cooperating movable clamp members; and to provide in such a miter box a novel arrangement and construction of stationary clamp means and saw guides associated therewith to form a guide slot.

In this application there is shown and described only the preferred embodiment of the invention simply by way of illustration of the practice thereof, as by law required. However, it is recognized that the invention is capable of other and different embodiments, and that the various details thereof may be modified in various ways; therefore the drawing and description herein are to be considered as merely illustrative and not as exclusive.

In the accompanying drawing:

Figure 1 represents a top plan view of the preferred embodiment of the invention;

Figure 2, a section on the line 2—2 of Figure 1, looking in the direction of the arrows;

Figure 3, a section on the line 3—3 of Figure 1, looking in the direction of the arrow; and,

Figure 4, a detail plan view of one of the movable clamp members of the preferred form of the invention illustrated in Figures 1, 2 and 3.

Referring now in detail to the accompanying drawing wherein is illustrated the present preferred embodiment of the invention, and first considering the entire structure rather generally, it may be seen that the same comprises: a rigid sheet material base or body, designated 1 in its entirety, in which are formed two relatively angularly disposed rearwardly converging downwardly pressed corrugations 2 defining linear guide channels in the upper surface of the base 1;

5 a pair of upright supports 3 integrally connected to the base 1 at the respective converging rear ends of the corrugations 2 and formed with upwardly extending rearwardly pressed corrugations 4 communicating at their lower ends with said respective corrugations 2 so as to form upwardly disposed continuations thereof; stationary clamp plates 5 secured to said respective supports 3 and having relatively spaced parallel saw guides 6 connected to their respective adjacent edges to define a guide slot 7 for a saw; movable clamp members 11 having guides or portions 15 slidably received in and conforming to the respective corrugations or channels 2 to maintain said members 11 at all times in alignment with their respective cooperating stationary clamp plates 5; and means such as the operating screws 10 threaded through upturned lugs 9 of the base 1 for causing movement of said respective members 11 towards and away from their cooperating members 5.

Referring now more in detail to the specific construction and arrangement of parts of the preferred embodiment, it is to be noted that the 15 hereinbefore mentioned base 1, supports 3, and lugs 9, are particularly adapted for economical manufacture by suitable sheet metal stamping operations from a single substantially sector shaped sheet steel or other rigid sheet material blank, the supports 3 being turned upright at an angle to each other and preferably perpendicularly relative to the base 1, as shown.

Obviously the upturned supports and lugs 3 and 9 respectively, and the downwardly pressed corrugations 2, will serve to reinforce and stiffen the side portions of the base 1, however in addition it is desirable to provide some means for strengthening and stiffening the medial portion of said base between the corrugations 2, as for instance the downwardly pressed transversely extending corrugation 12 and the downwardly turned flange 14 at the front edge of the base. It is highly desirable to have the lowermost surfaces of the corrugations 2 and 12, and the lower edge of flange 14, all disposed in the same plane, as shown in Figure 2, to rest flush against a flat supporting surface A and thus provide firm non-wobbling support for the miter box.

In order to permit secure fastening of the 50 base 1 to the flat surface A, which may represent the top of a work table or bench or the like, by widely spaced unobtrusive fastening means, it is preferred that screw holes 8 may be provided preferably at the rear or converging 55 ends of the respective corrugations 2, said screw

holes 8 preferably being countersunk so that the heads of fastening screws (not shown) received therein will not obstruct the path of movement of the respective clamp members 11. Although any of a number of various fastening arrangements and dispositions of screw holes may be employed, the foregoing arrangement is preferable in that it serves to maintain the bottoms of the corrugations 8 firmly against the supporting surface A, the securing screws will be widely spaced to prevent twisting or turning of the miter box, and will additionally be disposed so as not to obstruct the placing of the work pieces or the movement of the clamp members 11.

Each of the hereinbefore mentioned corrugations 2 is preferably of uniform depth through its length so as to permit uninterrupted sliding movement of the guides or portions 15 of members 11 therein, however it is desirable, though not essential, that the upward continuation or portion 4 of each said corrugation should be of maximum depth at its lower end juncture with its respective corrugation 2 and become increasingly shallower towards its upper end, as shown in Figures 2 and 3, whereby the rearwardly projecting bottom of each said corrugation 4 constitutes a diagonal forwardly inclined brace for its respective support 3 and the stationary clamp plate 5 secured thereto, and thus serves to rigidly brace and maintain its respective support 3 in upright position to withstand a large amount of pressure exerted by its cooperating movable clamp member 11. This same bracing and supporting action will of course be present, though probably to a somewhat smaller degree, even though corrugations 4 are not formed with sloping bottoms having their maximum depth at their lower ends.

Although the clamp plates 5 might conceivably be omitted, in most cases they are highly desirable inasmuch as it is impractical to turn up from the base 1 supports, such as 4, which would be of proper size and shape to cooperate most effectually with the movable clamp members 11, and to which saw guides such as 6 could be efficiently and economically attached. The clamp plates 5 are formed as separate preferably rectangular preferably stamped sheet metal members and may be secured to their respective supports 3 in any suitable manner, as by spot welding, and the saw guides 6 preferably constitute integral rearwardly bent parallel portions of said plates 5. Preferably said plates 5 are disposed at right angles to each other and the guide slot 7 defined by said guides 6 is disposed in a direction bisecting the angle defined by said plates 5. It is to be understood of course that the saw guides 6 may be omitted where it is desired to use the device exclusively merely as a clamp for assembling previously mitered work pieces.

The movable clamp members 11 are each formed with a preferably integral guide portion or key 15 to be conformingly slidably disposed in the respective corrugations or channels 2, as hereinbefore mentioned, and in the preferred form of the invention illustrated the members 11 project laterally on either side of their respective channels 2 and have straight lower edges 16 which may be disposed in slidable engagement with the base 1 and, together with the guides or keys 15, prevent the members 11 respectively from rotating with their operating screws 10, though it is thought to be apparent

that the guides 15 may be relied upon by themselves to prevent such rotation.

The operating screws 10 illustrated merely comprise one convenient means for producing movement of the movable clamp members 11 towards and away from their respective stationary members or plates 5 and various equivalent means may be employed within the scope of the invention.

- 10 In the illustrated preferred arrangement of said operating screws 10, each said screw 10 is preferably in the form of an eyebolt, the annular portion 17 of which serves as convenient gripping and rotating means, and the free end 15 of each said screw is suitably rotatably connected to its respective member 11 as by passing it through a countersunk hole 18 formed in the medial portion of said member and upsetting the metal at the end of said screw into the countersunk portion of said hole 18, as at 20 19, to form an enlargement preventing removal of said member 11 from screw 10. It is to be noted also that said enlargement 19 lies flush with the surface of the clamp member 11 and therefore will not tend to mar the work piece 25 engaged thereby.

As a precaution against stripping the threads from the threaded bores 20 in each of lugs 9, it is desirable to form at the mouth of each said bore 20, an annular flange 21 serving to increase the thickness of the sheet material surrounding said bore and accordingly the axial extent and holding power of the threads in said bore 20.

- 30 The hereinbefore described device may be operated in the usual conventional manner, as by clamping the work piece, which may consist of picture frame parts, moulding strips, etc., of various sizes and widths, between either of the sets of clamp members 5 and 11, whereby the 35 work piece may be cut at the desired angle by a saw having its blade slidably disposed in and guided by the slot 7 between guides 6. Thereafter, if desired, two of such pieces may be 40 clamped at an angle to each other and suitably held by the respective sets of clamps or clamp members 5, 11, while their previously sawed ends 45 are joined together at an angle by any suitable means.

It may be seen from the foregoing that the 50 novel arrangement of corrugations 2 and 4 set forth serves to rigidly reinforce the miter box and particularly the upright supports 3 thereof, and also the portions 2 of said corrugations 55 serve as guide channels for the movable clamp members 11, thus making for a strong efficient, economically manufactured miter box. Also the arrangement of clamp plates 5 and guides 6 carried by the supports 3 is believed to result in a novel, efficient, economical and highly useful construction.

What is claimed is:

1. A miter box comprising, a substantially sector shaped base plate formed with two relatively angularly disposed linear guide channels therein, a pair of upright supports integrally connected to said plate at the converging ends of said respective guide channels, each said support extending in a transverse plane relative to its respective guide channel and being formed with a reinforcing channel constituting an angularly upwardly disposed continuation of said guide channel, stationary clamp members secured to said respective supports and disposed in converging planes relative to each other, relatively parallel spaced saw guides integral with

the respective converging edges of said stationary clamp members to define a guide slot bisecting the dihedral angle defined by said members, upwardly turned lugs integrally attached to said base plate at the respective diverging ends of said guide channels, operating screws threaded through said respective lugs in directions parallel to said respective guide channels, movable clamp members respectively rotatably secured to the ends of said screws for movement therewith towards and away from said respective stationary clamp members, and guides carried by each of said members and conformingly disposed for sliding movement in said respective guide channels to maintain said movable clamp members at all times in alignment with their respective cooperating stationary clamp members.

2. A miter box comprising, a base formed with two relatively angularly disposed linear guide corrugations therein, a pair of upright supports integrally connected to said base at the converging ends of said respective guide corrugations, each said support extending in a transverse direction relative to its respective guide

corrugation and being formed with a reinforcing corrugation constituting a relatively angularly disposed upwardly extending continuation of said guide corrugation, stationary clamp members secured to said respective supports in converging planes relative to each other, relatively spaced parallel saw guides integral with said stationary clamp members to define a guide slot, upwardly turned lugs integrally attached to said base at the respective diverging ends of said guide corrugations, operating screws threaded through said respective lugs, movable clamp members respectively rotatably secured to said screws for movement therewith towards and away from said respective stationary clamp members, and guide portions carried by each of said members and conformingly slidably disposed for movement in said respective guide corrugations whereby said movable clamp members are maintained in alignment with their respective stationary members and also prevented from rotating relative thereto.
